US0D1037950S

(12) **United States Design Patent** (10) **Patent No.:** **US D1,037,950 S**
(45) **Date of Patent:** **** Aug. 6, 2024**

(54) **REAR BUMPER LIP DIFFUSER FOR AUTOMOBILE**

(71) Applicant: **Guo Xiong Xian**, Kent, WA (US)

(72) Inventor: **Guo Xiong Xian**, Kent, WA (US)

(**) Term: **15 Years**

(21) Appl. No.: **29/798,131**

(22) Filed: **Jul. 6, 2021**

(51) LOC (14) Cl. **12-16**

(57) **CLAIM**

The ornamental design for a rear bumper lip diffuser for automobile, as shown and described.

DESCRIPTION

FIG. 1 is a perspective view of the rear bumper lip diffuser for automobile, showing the new design;

FIG. 2 is an alternative view of the rear bumper lip diffuser for automobile thereof;

FIG. 3 is a front elevational view of the rear bumper lip diffuser for automobile thereof;

FIG. 4 is a rear elevational view of the rear bumper lip diffuser for automobile thereof;

FIG. 5 is a left side elevational view of the rear bumper lip diffuser for automobile thereof;

FIG. 6 is a right side elevational view of the rear bumper lip diffuser for automobile thereof;

FIG. 7 is a top plan view of the rear bumper lip diffuser for automobile thereof; and,

FIG. 8 is a bottom plan view of the rear bumper lip diffuser for automobile thereof.
